(57) **CLAIM**

The ornamental design for a peanut-shaped earplug with paddle handle, as shown and described.

DESCRIPTION

FIG. 1 is a front perspective view of a peanut-shaped earplug with paddle handle in accordance with the new design;

FIG. 2 is a rear perspective view thereof;

FIG. 3 is a side elevation view thereof;

FIG. 4 is a side elevation view thereof, for the side opposite that of FIG. 3;

FIG. 5 is a side elevation view thereof, for the side 90 degrees from that of FIG. 4;

FIG. 6 is a side elevation view thereof, for the side opposite that of FIG. 5;

FIG. 7 is a front elevation view thereof;

FIG. 8 is a rear elevation view thereof;

FIG. 9 is a side elevation view of a second embodiment of the peanut-shaped earplug with paddle handle showing a user inserting the earplug into an ear;

FIG. 10 is a front perspective view of the peanut-shaped earplug with paddle handle in FIG. 9;

FIG. 11 is a rear perspective view thereof;

FIG. 12 is a side elevation view thereof;

FIG. 13 is a side elevation view thereof, for the side opposite that of FIG. 12;

FIG. 14 is a side elevation view thereof, for the side 90 degrees from that of FIG. 13;

FIG. 15 is a side elevation view thereof, for the side opposite that of FIG. 14;

FIG. 16 is a front elevation view thereof; and,

FIG. 17 is a rear elevation view thereof.

The broken lines shown in FIG. 9 are provided to illustrate environment and form no part of the claimed design. The remaining broken lines shown in the drawings represent internal boundaries with the line itself and the area within forming no part of the claimed design.

1 Claim, 9 Drawing Sheets
